UNITED STATES PATENT OFFICE.

ROBERT C. ELLIOTT, OF TERRE HAUTE, INDIANA.

MUSIC-LEAF TURNER.

SPECIFICATION forming part of Letters Patent No. 769,155, dated September 6, 1904.

Application filed December 8, 1903. Serial No. 184,261. (No model.)

To all whom it may concern:

Be it known that I, ROBERT C. ELLIOTT, a citizen of the United States, residing at Terre Haute, in the county of Vigo and State of Indiana, have invented certain new and useful Improvements in Music-Leaf Turners; and I do hereby declare the following to be a full, clear, and exact description of the invention, such as will enable others skilled in the art to

10 which it appertains to make and use the same.

This invention relates to turners for sheet-music; and it consists in the novel construction and combination of the parts hereinafter fully described and claimed.

15 In the drawings, Figure 1 is a front view of the music-leaf turner. Fig. 2 is a partial rear view of the same. Fig. 3 is an end view of the same.

A is a desk or back-plate for the sheet-music to rest against.

B is a stationary clamping-jaw secured to the middle part of the desk.

C is a sliding clamping-jaw provided with guide-pins c, which slide in guide-slots b in 25 the desk A.

D is a bar for operating the sliding jaw and provided with a finger-piece d, which projects slightly at one end of the desk.

E is a spring which is secured to the back 30 of the desk and which engages with a pin e on the sliding jaw and presses it toward the said stationary jaw. The middle part of the music where folded is clamped between the two said jaws, and the bottom edges of the 35 leaves rest on the ledges a, which project at the bottom of the desk.

F represents arms which prevent the cover 40 portions of the piece of music from being turned. A lug f projects downwardly at each end of the desk and has a spring G secured to it. The arm F has a pivot f', which projects from it at a right angle and which is journaled in a bearing g on the end of the said spring. The arm is formed of a piece of 45 wire, and the pivot is formed by bending it. The end of the piece of wire is rebent beyond the pivot to form a heel g', which is arranged parallel to the said pivot. This heel bears against the desk or the lug projecting there-

from, so that the spring presses the free end 50 of the arm against the cover-sheet.

H represents the turning-arms, which are pivoted on a pin h, secured to the middle portion of the lower part of the desk. Each turning-arm has a spring-clip h' of any approved construction for engaging with a leaf of music, and this spring-clip is secured to the free end of the said arm.

I represents the two levers for operating the turning-arms. These levers are provided 60 with eyes I', which are slidable longitudinally on the arms H. Each lever I is secured to the upper end of a shaft i, which is journaled in a bearing i', secured to a bracket J. The bracket J is secured to the middle part of the 65 bottom of the desk A, and j is a shaft carried by the lower part of the said bracket. A pinion K is secured on the lower end of each shaft i, and m and m' are two pairs of toothed segments, said segments being arranged one 70 on each side of each of the said pinions and gearing into their teeth. Each toothed segment is provided with a bearing n, which is journaled on the shaft j and provided with a finger-piece N for operating it. In order to 75 facilitate the construction of the device, each finger-piece is formed separate from the segment to which it pertains and is provided with a separate bearing n'. The stems or shanks 80 of the toothed segment and of the finger-piece are secured together, so that the bearings n and n' project in opposite directions.

O represents angle-shaped guide-plates, of 85 spring metal, which are secured to the bracket J and which bear against the backs of the toothed segments, so that the said segments are held in gear with the toothed pinions.

P is a cover-plate which is hinged to the 90 top part of the bracket J and which protects the segments and pinions from injury.

The back of the desk is provided with any approved clamping or fastening devices for holding the desk connected to any convenient support. R is a dovetailed socket secured to the back of the desk and which forms a slip-joint for engaging with the said clamping or fastening devices.

The music is held in position by the clamp-

ing-jaws, as hereinbefore described, and the leaves to be turned are inserted in the spring-clips. The leaves are turned over by depressing one of the finger-pieces N. These finger-pieces are arranged in pairs, and one turns the leaf in one direction and the other in the opposite direction. The whole device is very simple and compact and is not liable to get out of order.

10. What I claim is—

1. In a music-leaf turner, the combination, with a desk provided with a stationary clamping-jaw at its middle part and guide-slots, of a slidable clamping-jaw provided with guide-pins which slide in the said slots, an operating-bar for the said slidable jaw provided with a finger-piece which projects at one end of the said desk, a spring which presses the said jaws together, a leaf-turning arm pivoted to the said desk in line with the said jaws, an operating-lever pivoted to the said desk out of line with the said jaws and provided with an eye which is slidable longitudinally on the said turning-arm, and operating mechanism for turning the said lever back and forth.

2. In a music-leaf turner, the combination, with a desk provided with means for supporting the music, and a bent spring secured to the lower part of the said desk; of a retaining-arm having a bearing at its lower end which is pivoted in the free end portion of the said spring and having also a heel arranged parallel to the said pivot-bearing and engaging with the desk, a leaf-turning arm pivoted to the said desk to one side of the said retaining-arm, an operating-lever pivoted to the said desk out of line with the pivot of the said leaf-turning arm and provided with an eye which is slidable on the said leaf-turning arm, and operating mechanism for turning the said lever back and forth.

3. In a music-leaf turner, the combination, with a desk provided with means for support-

ing the music, and a bent spring secured to the lower part of the said desk and provided with a bearing at its free end; of a retaining-arm formed of wire and having a pivot at its lower end bent at a right angle to its main portion and journaled in the said bearing and having also a rebent portion arranged parallel to the said pivot and forming a heel which is pressed against the desk by the said spring, a leaf-turning arm pivoted to the said desk to one side of the said retaining-arm, an operating-lever pivoted to the said desk out of line with the pivot of the said leaf-turning arm and provided with an eye which is slidable on the said leaf-turning arm, and operating mechanism for turning the said lever back and forth.

4. In a music-leaf turner, the combination, with a desk provided with means for supporting the music, of a leaf-turning arm pivoted to the said desk, an operating-lever provided with an eye which is slidable longitudinally on the said turning-arm, said lever being pivotally supported from the said desk out of line with the pivot of the said operating-lever, and operating mechanism for turning the said lever back and forth.

5. In a music-leaf turner, the combination, with a desk provided with means for supporting the music, of a pivoted leaf-turning arm, a vertical shaft, an operating-lever secured to the said shaft and engaging with the said arm, a toothed pinion secured to the said shaft, toothed segments engaging with the said pinion, and angle-shaped guide-plates of spring metal which bear against the backs of the said toothed segments.

In testimony whereof I affix my signature in presence of two witnesses.

ROBERT C. ELLIOTT.
